UNITED STATES PATENT OFFICE.

LEWIS A. BAKER, OF ELGIN, ILLINOIS.

CAN-FILLING MACHINE.

1,119,389.

Specification of Letters Patent.

Patented Dec. 1, 1914.

Application filed February 14, 1913. Serial No. 748,307.

To all whom it may concern:

Be it known that I, LEWIS A. BAKER, a citizen of the United States, and a resident of Elgin, in the county of Kane and State of Illinois, have invented certain new and useful Improvements in Can-Filling Machines; and I do hereby declare that the following is a full, clear, and exact description thereof, reference being had to the accompanying drawings, and to the characters of reference marked thereon, which form a part of this specification.

This invention relates to improvements in can filling machines and refers more specifically, in one aspect of the invention, to a machine adapted to fill fruit cans with syrup after the fruit has been supplied thereto, prior to the sealing of the can, and to valve mechanism for controlling the flow of the syrup to the cans.

The invention is herein shown as applied to the general type of machine illustrated in my prior United States Patent, No. 910,265, granted to me on the 19th day of January, 1909. Said type of machine embraces a central tank or reservoir to contain the fluid or syrup to be fed to the cans, and a plurality of valve devices for intermittently discharging the liquid into the cans placed beneath the valve devices, the reservoir being rotated about its axis and the machine being provided with a rotative carrier means by which the cans are supported while being filled and constructed to raise the cans to and lower the same away from the valve devices.

The invention consists in the combination and arrangement of the parts herein shown and described and more particularly pointed out in the appended claims.

In the drawings:—Figure 1 is a side elevation of a valve device embodying my invention, with a part of the reservoir or tank shown in section. Fig. 2 is a vertical section thereof. Fig. 3 is a detail of the lower end of the vent tube for the filling device and its guard shoe. Fig. 4 is a section taken on the line 4—4 of Fig. 2.

As shown in the drawings, 10 designates a portion of the central tank or reservoir. 11, 12 designate the two parts of the filling tube which extends upwardly through the tank, the part 12 of which extends through an opening in the tank bottom 13 and depends below said bottom. The upper tube part or member 11 is seated at its lower end in a re-

cessed portion of the upper end of the lower tube part or section 12. The opening in the tank bottom through which the two-part tube extends is counterbored to receive the upper flanged end 14 of the lower tube section 12. The filling tube thus made up is clamped to the tank bottom by a lock nut 15 which is screw-threaded to the lower tube section 12 and bears against the under side 65 of the tank bottom. The filling tube, thus made up of the principal parts 11 and 12, may be otherwise made and fixed to the tank bottom. The construction herein shown, however, provides a ready means for 70 attaching the tube to the tank whereby it may be readily assembled and readily taken apart for cleaning purposes.

16 designates a sleeve which fits upon the lower end of the filling tube and is adapted 75 to slide up and down thereon. Its downward movement thereon is limited by a shoulder 16'. The said sleeve terminates at its lower end in a bell-shaped mouth 17 to the lower end of which the upper, open ends 80 of the cans A are presented. The lower rim of said bell-shaped mouth is grooved to receive a yielding ring 18 against which the mouths or edges of the open ends of the cans are pressed to thereby bring the can accurately to the mouth, notwithstanding slight irregularities in its presentation. Further the yielding ring also constitutes a sealing ring to prevent the escape of air or liquid between the can and the bell-shaped mouth 85 17 when the can is raised thereagainst. The said bell-shaped mouth is made sufficiently 90 large to receive the upper layers of fruit in the can which when inserted in the can in a raw state are piled substantially above the 95 level of the can mouth, so that when they are later cooked and, therefore, drop, the can is substantially filled. The extension of the fruit into the nozzle mouth has the effect to decrease the volume of air within said 100 mouth.

The discharge tube, comprising the sections 11 and 12, is provided, within the tank 10, with an opening 19 through which liquid flows from the tank to the filling tube. 105 The lower end of the filling tube is provided, within the bell-shaped mouth 17, with a conical valve seat 22 which surrounds the discharge opening of the filling tube. Said opening is adapted to be closed 110 and to be controlled by means of a vertically movable conical valve 23 that is carried by

the lower end of a stem 24 which extends upwardly through the filling tube and is adapted for engagement at its upper end with suitable valve controlling means. The 5 said valve 23 is shown as hingedly connected to the lower end of the stem by means of a pin 25 which extends transversely through the lower reduced, headed end of the stem and through a circular flange which extends upwardly from the valve piece and 10 surrounds the headed end of the valve stem. This arrangement permits the valve to be accurately seated against its seat 22, notwithstanding slight irregularities of fit of 15 the seat and valve. The valve stem 24 is provided with radial guide arms 26 which engage the filling tube to hold the valve stem centrally within the tube. This construction also permits the valve stem and 20 valve to be readily removed from the filling tube for the purpose of cleaning the parts. The said valve normally rests on its seat to close the filling tube by gravity, and it is lifted to open the filling tube by mechanism 25 made as follows: 27 designates a vertically movable lift bar that is supported and guided in bearings 28, 28 carried by the adjacent wall of the tank. Attached to the upper end of the lift bar is a lift finger 29 30 which extends inwardly toward the valve stem 24 and is offset downwardly at 30 to engage under a head or block 31 carried by the upper end of the valve stem 24. The said lift finger is apertured to fit over the 35 upper end of the lift bar and is held in place thereon by a set screw 32, whereby it may be adjusted vertically on the lift bar. The lift bar is provided at its lower end, below the lower bearing 28, with the laterally extending arm 33 which carries a roller 36 40 that is adapted to ride on a cam 37 suitably fixed to the frame of the machine, as, for instance, in the manner shown in my aforesaid U. S. Letters Patent, No. 910,265, granted 45 on the 19th day of January, 1909.

In the closed or normal position of the valve 23 and its actuating mechanism, the offset end 30 of the lift finger 29 is spaced a distance below the head 31 of the valve stem 24. As shown in the construction in my aforesaid patent, the lift bar is preliminarily raised, when the cans are presented to the filling tubes, so as to raise the bearing roller 36 in position to ride upon the lower, 50 entering portion of the valve opening cam 37. This preliminary raising of the lift bar does not open the valve 23, but merely brings the lift finger 30 against the head 31 of the valve stem. In the continued rotation of the reservoir and the filling tubes 55 carried thereby, the lift bar is further raised by the lifting or raising cam 37 so as to open said valve. If no can be presented to a given filling tube at a time when the 60 bearing roller 36 of its valve actuating

mechanism reaches the rising end of the cam 37, the said bearing roller will not be raised to the level of the rising end of the cam, but will pass beneath the cam, and the valve associated therewith will not be lifted. The means herein shown for so preliminarily raising the lift bar consists of a lateral lug or extension 40 on the bell shaped mouth piece 17 which lies under the lift bar and is adapted, during the preliminary lift 70 of the parts, to engage the lower end of the lift bar for the purpose stated, the sleeve 16 of the bell shaped mouth sliding upwardly on the tube section 12 during the 75 preliminary lifting movement.

42 designates a vent tube which is adapted to extend downwardly into a can that is presented to the associated filling tube so that when the liquid is delivered to the can and the vent tube is sealed by the rise of the 80 liquid in the can the supply of liquid to the can is cut off. The said vent tube extends upwardly through openings in the bearing members 28, 28 of the lift rod and fits loosely in said openings. The vent tube 42 has a tight fit in a stuffing box 45 carried by the bell shaped mouth piece 17. It is held in 85 adjustable positions by its fit with the stuffing box 45. The upper end of said vent tube is adapted to be closed by a valve plug 46 which 90 is carried by the lift finger 29. As herein shown, the said valve plug 46 is carried by and within the upper end of a short tube 47 that is fixed to the lift finger in any suitable manner, said tube 47 extending downwardly 95 over the upper end of the vent tube for a short distance. The lug is shown as screw-threaded to the closed end of the tube 47 which latter has a slip fit with the opening of the arm 29 through which it extends 100 so that the plug may thereby be adjusted toward and from the vent tube. The valve plug 46 is provided to prevent material leaking from the vent tube at a time when the main valve 23 is closed and no can is below 105 the same. The liquid which remains in the vent tube, after a can has been filled and the flow cut off therefrom, is discharged into the next can presented thereto at the time the vent tube valve 46 is raised, the can being 110 at this time raised up against the bell shaped mouth 17 and in position to receive all the liquid which may flow or drip from the vent tube. By reason of the fact that the liquid syrup is relatively thick and is, therefore, relatively sluggish in its movement in passing downwardly into the interstices between the pieces of the can contents, the liquid may rise a distance above the level of the top of the can into the nozzle mouth 17 115 before the filling flow is entirely stopped, the liquid subsequently settling about the pieces to the proper level at the top of the can.

As a further improvement I have pro- 120

vided at the lower end of the vent tube a guard or shoe 50 that is attached to and carried by the vent tube in any suitable manner, and is curved at its lower end 51 downwardly and laterally past the open end of the vent tube. Said guard is transversely curved on a radius considerably greater than that of the vent tube, and the laterally turned end 51 thereof is directed toward and is located near the side of the can. The guard is provided in order to prevent the fruit or other product in the can, to which the syrup is supplied, from being impaled upon the lower end of the vent tube and thereby clog said tube and defeat its normal venting and sealing function.

In order to prevent the liquid which may be forced upwardly through the relatively small vent tube and out of the upper end thereof, from flowing indiscriminately over the machine, I have provided means for directing such overflow as may occur back to the tank or reservoir 10. For this purpose the tube section 47, into which the upper end of the vent tube extends, is provided around the vent tube with a downwardly inclined drain plate 55 to direct any drippings from the upper end of the vent tube to a slot or opening 56 at the inner side of the section 47. The upper lift bar bearing 28, or a tubular extension 58 thereof is provided beneath the tube section 47, with an inwardly inclined trough 59 to receive such dripping and direct the same back to the reservoir or tank 10.

It will be understood that the structural details of the invention described may be somewhat varied within the spirit and scope of the invention and that the invention is not limited to such details except as hereinafter made the subject of specific claims and as imposed by the prior art.

I claim as my invention:—

1. A can filling machine comprising a reservoir having a discharge opening which empties into a receptacle presented thereto, a valve for controlling said discharge opening, with means for actuating the valve, a vent tube adapted to project into the top and at one side of a receptacle presented to said discharge opening, a valve for controlling the vent tube, and a guard carried by the lower end of the vent tube and extending across the lower end thereof toward the adjacent side of the can.

2. A can filling machine comprising a reservoir having a discharge opening which empties into a receptacle presented thereto, a valve for controlling said discharge opening, with means for actuating the valve, a vent tube adapted to project into a receptacle presented to said discharge opening, and means whereby the vent tube may be vertically adjusted to vary the depth of its penetration into the receptacle being filled,

and a vertically adjustable valve to close said vent tube.

3. A can filling machine comprising, in combination, a reservoir having a discharge opening to empty into a receptacle presented thereto with means for controlling the flow of the liquid therethrough and a vent tube adapted to extend into the top and at one side of the receptacle and provided at its lower end with a guard which extends across the lower end of said tube.

4. In a can filling machine, a vent tube with means for controlling the flow of air therethrough, and a guard fixed to the lower end of the tube and extending across the lower end thereof.

5. A can filling machine comprising a reservoir having a discharge opening which empties into a receptacle presented thereto, a valve for controlling said opening, with means for actuating the valve, a vent tube adapted to extend at its lower end into the receptacle, a valve for closing the upper end of said vent tube, having means whereby it is actuated from the discharge opening valve actuating means, said vent tube being vertically adjustable, and means for vertically adjusting its closing valve.

6. A can filling machine comprising a reservoir having a discharge opening which empties into a receptacle presented thereto, a valve for controlling said opening provided with a stem extending upwardly through said reservoir, a lift bar at the side of the reservoir, having connections with said stem to open said valve, a vent tube exterior to the reservoir adapted to project into a receptacle below and open at its upper end, a valve carried by said lift bar for closing the upper end of the vent tube, said vent tube being vertically adjustable, and means for vertically adjusting the vent tube valve relatively to said lift bar.

7. A can filling machine comprising a reservoir having a discharge opening which empties into a receptacle presented thereto, a valve for controlling said opening provided with a stem which extends upwardly through the reservoir, a lift bar at the side of the reservoir, having connections with said stem to open said valve, a vent tube exterior to the reservoir adapted to project into a receptacle below and open at its upper end, a valve carried by said lift bar for closing the upper end of the vent tube, and means for directing liquid which escapes from the upper end of the vent tube back to the reservoir.

8. A can filling machine comprising a reservoir having a discharge opening which empties into a receptacle presented thereto, a valve for controlling said opening provided with a stem which extends upwardly through the reservoir, a lift bar at the side of the reservoir, having connections with

said stem to open said valve, a vent tube exterior to the reservoir adapted to project into a receptacle below and open at its upper end, a valve for closing the upper end of said vent tube, a housing carried by the lift rod into which the upper end of the vent tube extends and an inclined drip plate within said housing surrounding the upper end of the tube for directing fluid to the reservoir.

9. A can filling machine comprising a reservoir, a filling tube depending therefrom and communicating therewith and having at its lower end a discharge opening, a valve for controlling said discharge opening, with means for actuating the same, a sleeve slideable on said filling tube and terminating in a bell shaped mouth to engage and seal the upper end of the receptacle, said filling tube terminating above the level of the lower edge of said mouth and the mouth being made of a size to receive a portion of the contents of the receptacle, and means whereby the vertical movement of said sleeve controls said filling tube discharge opening valve.

10. A can filling machine comprising a reservoir, a filling tube depending therefrom and communicating therewith and having at its lower end a discharge opening, a valve for controlling said discharge opening, a lift rod for actuating said valve, a mouth piece slideable on the filling tube to

engage and seal the upper end of the receptacle and provided with means for actuating said lift rod, a controlling cam coöperating with the lift rod to open said valve, a vertically adjustable vent tube adapted to dip at its lower end into said receptacle and a valve carried by the lift rod to control the opening in the upper end of said vent tube, with means to vertically adjust said latter valve.

11. A can filling machine comprising a reservoir, a filling tube depending therefrom and communicating therewith and having at its lower end a discharge opening, a valve for controlling said discharge opening, with means for actuating the same, a sleeve slideable on said filling tube and terminating in a bell shaped mouth to engage and seal the upper end of a receptacle, a lift rod to control the filling tube valve, a lug projecting from said sleeve to engage the lift rod to preliminarily raise it when a receptacle presented to the filling tube raises said sleeve, a lift rod controlling cam above said mouth and a projection on the lift rod adapted to be lifted into engagement with said cam.

In testimony, that I claim the foregoing as my invention I affix my signature in the presence of two witnesses, this 22nd day of January, A. D. 1913.

LEWIS A. BAKER.
